UNITED STATES PATENT OFFICE.

HORACE M. SPRAGUE, OF DENVER, COLORADO, ASSIGNOR TO WILLIAM GROSS, OF MINNEAPOLIS, MINNESOTA.

GEAR-CONTROLLED PADLOCK.

1,095,431.

Specification of Letters Patent.

Patented May 5, 1914.

Application filed July 7, 1913. Serial No. 777,773.

To all whom it may concern:

Be it known that I, HORACE M. SPRAGUE, a citizen of the United States of America, residing in the city and county of Denver 5 and State of Colorado, have invented a new and useful Gear-Controlled Padlock, of which the following is a specification.

My invention relates to improvements in gear controlled locks, and the objects of my 10 invention are: first, to provide a lock having a combined locking and key mechanism, and second, to provide a lock in which a gear and pinion mechanism is combined with an oscillating movement to lock and unlock 15 the lock. I attain these objects by the mechanism illustrated in the accompanying drawings, in which:

Figure 1 is a longitudinal sectional view showing the preferred form of my improved 20 lock, the key being partially inserted. Fig. 2 is also a longitudinal sectional view of the same, on the line 2—2 of Fig. 1. Fig. 3 is a transverse sectional view thereof, on the line 3—3 of Fig. 1, looking in the direction 25 of the arrow. Fig. 4 is an end view of the cap showing the bolt-receiving apertures therein. Fig. 5 is an end view of the lock, the cap, the bolts, and the toothed disks being removed. Fig. 6 is a side view of the 30 outer casing. Fig. 7 is a longitudinal sectional view of a modified form of the lock in which two pairs of toothed disks are employed, one pair being above the other and slightly to one side thereof. Fig. 8 is a 35 transverse sectional view on the line 8—8 of Fig. 7. Fig. 9 is a longitudinal sectional view of a further modification in which three toothed disks are arranged in progressive order, the plane of their axes being 40 inclined. Fig. 10 is a transverse sectional view on the line 10—10 of Fig. 9. Fig. 11 is a longitudinal sectional view of a still further modification in which a pinion shaft 45 takes the place of one of the toothed disks. Fig. 12 is a transverse sectional view on the line 12—12 of Fig. 11. Fig. 13 is a plan view of the form of key used in connection 50 with the lock shown in Fig. 1. Fig. 14 is an end view thereof. Fig. 15 is a transverse 55 sectional view of the form of key used in connection with the locks shown in Figs. 7 and 11. Fig. 16 is a transverse sectional view of the form of key used in connection with the lock shown in Fig. 9. And Fig. 17 60 is a view of one of the locking bolts.

Referring to the accompanying drawings, in which Figs. 1 to 6, inclusive, illustrate the preferred form of my improved lock; the numeral 1 indicates a cylindrical sleeve, which forms the casing of the lock. One end 60 of this sleeve is interiorly threaded for a suitable distance, and a cylindrical core 2 is inserted in the sleeve and extends from where the threads terminate, to and flush with the opposite end of the sleeve. The 65 core is secured in the sleeve by any suitable means, preferably by a rivet 3, which is finished flush with the surface of the casing. A cap block 4 is screwed into the threaded end of the sleeve or casing, and against the 70 end of the core 2. This block is provided with ears 5, between which one end of a semi-circular clasp or shackle 6, is pivotally secured. The other end of this clasp terminates in a reduced catch portion 7, which, 75 when the clasp is closed, fits into a correspondingly shaped recess 8 in the outer face of the block 4, the recess 8 extending from the center of the block through its threaded periphery, as shown in Fig. 1. The recess 8 is positioned to register with a corresponding recess 9 in the edge of the sleeve 1; when 80 the sleeve is given a quarter turn thus to release the clasp and allow the same to swing out, the clasp being locked by the margin of 85 the sleeve before the sleeve is turned to cause the recesses 8 and 9 to register. The manner of locking the block against turning 90 is accomplished in the following manner: Into the inner end of the block are drilled 95 four bolt-receiving apertures 10, the two outer apertures being on a slightly higher plane than the two inner apertures, and the apertures 10 register with bolt retaining apertures 11, in the core 2, which latter 100 apertures extend to within a slight distance of the opposite end of the core. Into the apertures 11 are placed coil springs 12, and against these springs are placed bolts 13 and 14, the forward portions of which, when the 105 apertures 10 and 11 register, are forced into the apertures 10 by the expansive force of the springs 12, and thus prevent the block 4 from being turned. The manner of retracting the bolts to release the block, is as follows: The rear portions of the bolts 13 and 14 are provided with annular teeth 15, which are engaged by pinion wire shafts 16, and 17, respectively, which have bearings in 110 transverse apertures 18, formed in the core

2, in which apertures the said pinion shafts turn loosely. I preferably employ four of these shafts, one for each of the outer bolts 14, and one for each of the inner bolts 13, the inner ends of each pair of aligned shafts 5 touching, as shown by Figs. 2 and 3. The core 2 is provided with parallel narrow slots or recesses 19, which are milled into it from one side, and which extend from its forward 10 end to within a slight distance of its rear or bottom end, the wall between them supporting the inner ends of the pinion shafts 16 and 17, as clearly shown by Fig. 3. These slots or recesses 19 form housings for irregularly toothed disks or gears 20 and 21, which are secured upon the shafts 16 and 17 respectively, the axial holes in the said disks having toothed marginal edges to correspond to the cross-sectional outline of the 15 pinion wire shafts, so that when they are placed upon the said shafts they are thereby keyed thereon, so as to rotate with the shafts. The gears 20 are preferably of less diameter than the gears 21, but the teeth thereon, as 20 shown, correspond in arrangement to the teeth on the disks 21, though a different arrangement of teeth for each of the gears 20 and 21 may be employed if desired. Parallel slots 22 are formed through the bottom of the core 2, which form shallow continuations of the slots 19, and extend through the periphery of the core. A portion of the lower edge of the wall between the slots 19 is also cut away, so that with 25 the inner surface of the sleeve 1, a U-shaped key slot is formed, as clearly shown in Fig. 5, in which may be inserted a key 23, of the form shown in Figs. 13 and 14, which are respectively a plan view and an end view of 30 said key. The upturned side ribs 24 of this key are notched or toothed to correspond to the toothed edges of the disks or gears 20 and 21, so that when the key is inserted in the key slot it first engages and turns the 35 gears 21, which turn the pinion wire shafts 17, which mesh with the toothed ends of the bolts 14, which are thereby retracted. Before the bolts 14 are fully retracted, the 40 end of the key begins to engage the gears 20 on the shafts 16, which latter shafts engage and retract the bolts 13, so that by the time the key is fully inserted, the bolts 13 and 14 are withdrawn from the apertures 10 in the 45 cap block, which permits the turning of either the said cap block or the casing until the respective recesses 8 and 9 register, when the shackle 6 may be turned on its pivot, so that its reduced end 7, passes out through the said registering recesses 8 and 9, thus 50 accomplishing the unlocking operation. The locking operation is accomplished by turning either the cap block or casing until the recesses 8 and 9 register, when the shackle 6 is turned to enter the recess 8 in the block, 55 as shown in Fig. 1; the casing is then turned 60 65

until the apertures 10 in the block register with the apertures 11 in the core, when the bolts 13 and 14 are sprung into the said apertures 10 by the expansive force of the springs 12. By having a separate shaft for each wheel, the chance of throwing the bolts 13 and 14 by any other means than by the proper key, is practically eliminated. As a further means of preventing picking of the lock, I place short blocks 24 in the bottoms 70 of the apertures 10, against which the forward ends of the bolts 13 and 14 abut, as shown clearly in Fig. 2, which blocks would drop, as the bolts are withdrawn, and prevent turning of the sleeve 1, unless the bolts 75 were fully retracted and held in this position. The shafts 16 and 17 are made of what is commonly known as pinion wire, which in cross-section is similar to an ordinary pinion wheel. 80 85

In Figs. 7 and 8, I illustrate a lock which embodies the same principle as the form of lock above described, but differs slightly in the arrangement of its toothed disks or gears. In this form of lock, the casing 1 is 90 the same as in Fig. 1, but its core 25 is provided with a substantially Z-shaped slot 26, which extends from its forward end, to within a short distance of its opposite end, and is continued through the latter end in 95 the form of a key slot 27, as shown, of the same outline, but of considerably less length. The parts of this slot which are off-set with respect to each other, form housings for pairs of irregularly-toothed gears 28 and 29, 100 the gears 28 being of less diameter than the gears 29. A gear 28 and a gear 29 are arranged in tandem order in each wing of the slot, the gears 29 being in advance of the gears 28, and these gears are mounted respectively upon pinion wire shafts 30 and 31, which are mounted in transverse holes 32, which extend through the core. The 105 shafts 30 engage the threaded ends of bolts 33, which are housed in apertures which extend to within a slight distance of the shafts 31, and the shafts 31 engage bolts 34, which are housed in apertures which extend nearly to the bottom end of the core. The gears 28 and 29 may be formed with any desired arrangement of teeth, and are operated by a 110 key 35, a cross-section of which is shown in Fig. 15. 115

In Figs. 9 and 10, a further modification of the lock is shown. In this form, I employ 120 a sleeve or casing 36, a portion of the bottom end of which is internally threaded as shown at 37. A core 38, which is threaded at its lower end, extends entirely through the sleeve and has integral ears—not shown 125 on its upper end, between which the shackle 39 is pivoted, the opposite end of the shackle fitting in a recess 40 in the end of the core, which is positioned to register with a corresponding recess 40^A in the end of the sleeve, 130

which is positioned the same as the recess 9, shown in Fig. 6. A longitudinal slot 41 is formed in the core on one side of its center, and three pinion wire shafts, 42, 43 and 44 extend transversely and at regular intervals through the core, but on different planes, the shaft 44 being nearest the axial center of the core, while the shaft 42 is farthest from the axial center of the core. Upon these shafts, and within the slot 41, are mounted gears 45, 46 and 47 respectively, which are irregularly toothed, and the arrangement of the teeth on each wheel being different from that of each of the others. Bolt apertures 45^A extend centrally through the core, at right angles to the shafts, and register with corresponding apertures 46^A in the sleeve 36. Bolts 47^A, similar to the bolt shown in Fig. 17, are carried by the apertures 45^A, and are projected into the holes 46^A in the sleeve, by springs 48, which bear against the opposite ends of the bolts. The toothed portions of these bolts are in mesh with the shafts 42, 43 and 44. A key slot 49 extends through the bottom of the core, one side of which is formed by the inner surface of the casing, the slot being substantially V-shaped in cross-section, as shown in Fig. 10. The key 50 for operating this lock, is of the form shown in cross-section in Fig. 16, one of its wings or blades being provided with three tiers of teeth, shaped to correspond to the teeth on the gears 45, 46 and 47, and when the key is inserted in the lock, it engages all of the gears at the same time, so that the bolts 47^A are retracted simultaneously, as the pinion shafts rotate with the gears. The shackle 39 is released as in the manner before described, by giving the sleeve 36 a partial rotation so as to cause the recesses 40 and 40^A to register.

Figs. 11 and 12 illustrate a still further modification in which I employ a casing 51, a portion of the lower end of which is internally threaded. A core 52, similar to that shown in Fig. 9, is inserted in the casing, its lower end being threaded to engage the threaded portion of the casing. The upper ends of this core and its casing are in all respects identical with the arrangement shown in Fig. 9, and a description thereof is unnecessary. The core 52 is provided with a longitudinal slot 53, on one side of its axial center, which terminates adjacent to the casing in a substantially Z-shaped bend. A pinion shaft 54 extends transversely through the core centrally of its width and at right angles to its axis, and carries a gear 55, which is housed by the slot 53. A second pinion shaft 56 extends transversely through the core, but on a plane farther from the axial center of the core than the shaft 54. The shaft 54 engages a bolt 57, and the shaft 56 engages a bolt 58, which bolts slide in

apertures in the core and are projected in opposite directions by springs 59, to enter registering holes in the casing, the shafts 54 and 56 engaging opposing sides of the bolts so that they are retracted in opposite directions. The shaft 56 carries no pinion and is engaged directly by the toothed end portion of a key 60, which is also provided with a toothed portion 61, which engages the gear 55, the key, which is of the form shown in cross section in Fig. 15, being inserted through a correspondingly shaped aperture 62, in the bottom of the core. By turning the gears, one tooth in either direction from a given position, a different arrangement or order of the teeth is presented, and as the teeth are irregularly formed, as many such changes in their order or arrangement is obtained as there are teeth on any one of the gears. Thus with one set of gears, combinations of teeth may be obtained, requiring as many different keys as there are teeth on a gear.

The form of lock herein described is practically indestructible, and the arrangement of its mechanism is such as to eliminate the chance of its being unlocked with any other than the proper key.

Having described my invention, what I claim as new and desire to secure by Letters Patent, is:

1. A lock as specified, comprising a body portion, a shackle pivotally and rotatably mounted in one end of the body portion, and adapted to be held by said body portion when in one position, and released when given a partial rotation thereon, locking means for preventing rotation of the said shackle, mechanism for retracting said locking means, and a key for operating said mechanism.

2. A lock as specified, comprising a body portion, a block rotatably secured in one end of said body portion, a shackle pivoted to said block, and adapted to be engaged by said body portion in one position of the block, and to be released by said body portion when the block is given a partial rotation, means for locking the block against rotation, mechanism for retracting the locking means, and a key for operating said mechanism.

3. A lock as specified, comprising a body, a block rotatably secured in one end of said body, a shackle pivoted at one end to said block, the free end of which is adapted to be engaged by the body in one position of the block, and released therefrom when the block is given a partial rotation, bolts carried by the body, which enter the block and normally prevent rotation of the same, mechanism for retracting the bolts, and a key for operating said mechanism.

4. A lock as specified, comprising a body, a block threaded in one end of the body hav-

- ing a radially disposed recess, a recess being formed on the end of the body, a shackle pivoted at one end to the block, the free end of which is adapted to enter the recess in the 5 block and to be held thereon by the body in one position of the block, and to be released when the block is turned to cause its recess to register with that in the end of the body, 10 spring-actuated bolts carried by the body, which enter the block and prevent rotation of the same, mechanism for retracting the bolts, and a key for operating the mechanism.
5. A lock as specified, comprising a body 15 having a threaded recess in one end, a block threaded in said recess having a radially-disposed slot in its outer end, a slot being formed in the rim of the body, a shackle pivoted at one end to the block, the free end of 20 which is adapted to enter the recess in the block, and to be held therein by the said rim in one position of the block and to be released when the block is turned to cause its slot to register with that in the rim of the 25 body, spring-actuated bolts carried by the body, which enter the block and prevent rotation of the same, gearing for retracting said bolts, and a key for operating said gearing.
- 30 6. A lock as specified, comprising a body consisting of a solid core and a sleeve rigidly secured upon the core and of greater length, the extended portion of said sleeve being internally threaded, and having a slot in its 35 rim, a block threaded in said extended portion and having a radial slot extending through its periphery, a shackle pivoted at one end to said block, the free end of which is adapted to enter the slot in the block, and 40 to be held therein by the said rim, in one position of the block, and to be released therefrom when the block is rotated to cause its slot and the slot in the said rim to register, 45 spring-actuated bolts in said core, which enter holes in said block and prevent the same from rotating, said bolts having toothed portions, pinion shafts in said core in mesh with the threaded portions of said bolts, gears on said pinion shafts, and a key for turning 50 said gears.
7. In a lock as specified, the combination of a body, a block rotatably secured in one end thereof, a shackle at one end of said
- block, the other end of which is adapted to be held by the body in one position of the 55 block and to be released when the block is given a partial rotation, spring-actuated bolts carried by the body, which enter and lock the block against rotation, said bolts having toothed portions, pinions carried by 60 the body in mesh with the toothed portions of said bolts, irregularly-toothed gears rigid upon said pinions, said body having a key slot in line with said gears, and a key toothed to correspond with said gears and adapted to 65 be inserted in said slot.
8. A lock as specified, comprising a body, a block rotatably secured in one end thereof, a shackle hinged at one end to said block, mechanism for locking the block against rotation, and a key for operating said mechanism to release the block, the free end of said shackle being engaged by the end of the body in one position of the block, and released therefrom when the block is given a partial 70 rotation.
9. A lock as specified, comprising a body consisting of a solid core and a sleeve secured thereon, of greater length than the core, the extended portion of the sleeve being 80 internally threaded, a block threaded in said extended portion, having a radial recess extending through its periphery, the rim of said sleeve being also provided with a recess, a shackle hinged at one end to said block, the 85 other end of which is adapted to enter the recess in the block and to be held therein in one position of the block and to be released when the block is rotated to cause its recess to register with that in the said rim, said 90 block and core having longitudinal, registering apertures, spring-actuated bolts in the core apertures which enter the apertures in the block, said bolts having toothed portions, pinions in mesh with said toothed portions, 95 irregularly-toothed gears rigid upon said pinions, and a key for engaging said gears, short circular blocks being loosely mounted in the holes of the block against which the ends of the bolts abut.
- 100 In testimony whereof I affix my signature in presence of two witnesses.

HORACE M. SPRAGUE.
